COMBINATION TOOL

Frank Rando, 59 Irving Ave.,
Brooklyn, N.Y. 11237

Filed Oct. 30, 1964, Ser. No. 82,397

Term of patent 14 years

(Cl. D54—13)

FIG. 1 is a top plan view of a combination tool, showing my design; and

FIG. 2 is a side elevational view of the same.

The side opposite that shown in FIG. 2 is substantially a mirror image thereof.

I claim:

The ornamental design for a combination tool, as shown and described.
